CLAIM

The ornamental design for a sippy cap for a bottle opening, as shown and described.

DESCRIPTION

FIG. 1 is a perspective view of the sippy cap for a bottle opening of the instant invention;

FIG. 2 is a left side elevation view thereof, the right side elevation view being identical thereto;

FIG. 3 is a front elevation view thereof;

FIG. 4 is a rear elevation view thereof; and,

FIG. 5 is a top elevation view thereof, the bottom elevation view being identical thereto.

The broken lines are for illustrative purposes only and form no part of the claimed design.
